ELECTRIC VALVE CIRCUIT

Kurt Herzog, Berlin-Charlottenburg, and Georg Vafiadis, Berlin-Treptow, Germany, assignors to General Electric Company, a corporation of New York

Application May 10, 1938, Serial No. 207,032
In Germany July 2, 1937

5 Claims. (Cl. 175—363)

Our invention relates to electric valve circuits and more particularly to excitation or control circuits for electric valve apparatus.

In excitation or control circuits for electric valve apparatus it is frequently desirable to employ both manual and automatic control means which control the conductivity of an associated electric valve apparatus. Particularly, in electric translating apparatus comprising electric valve means employing ionizable mediums such as gases or vapors, it is important to provide manually adjustable control means which enables the operator to transfer the control of the electric valve means from automatic means to the manual means. Furthermore, it is necessary to effect this transition from the automatic control means to the manual control means without causing a disturbance in an associated load circuit which may be fed by the electric valve means. In other words, it is important to effect this transfer of control without abruptly varying the conductivity of the electric valve means. There has been evidenced a decided need for improved control or excitation circuits which permit a smooth transition from automatic to manual control without causing transient conditions during the transfer operation.

It is an object of our invention to provide a new and improved electric valve circuit. It is another object of our invention to provide a new and improved control or excitation circuit for electric valve means.

It is a further object of our invention to provide a new and improved method for controlling electric valve apparatus.

In accordance with the illustrated embodiment of our invention we provide a new and improved control or excitation system for electric valve apparatus which energizes a direct current load circuit from an alternating current supply circuit. The electric valve apparatus may comprise a control member or a plurality of control members which control the conductivity of the electric valve means. The control or excitation system comprises automatic means which impresses on the control members periodic voltages which vary in phase in accordance with a predetermined controlling influence such as the voltage of the direct current load circuit. The control system also comprises a manually adjustable phase shifting circuit which introduces in series relation with the first periodic voltage a second periodic voltage which may be adjusted in phase with respect to the anode cathode voltage of the electric valve means. The automatic means may

be of the type designed to produce a voltage of peaked wave form and may comprise an electric discharge device of the controlled type which periodically transmits impulses of peaked voltage to the control member or members of the electric valve means. The electric discharge device is in turn controlled by a suitable circuit such as a voltage sensitive circuit or an amplifier which may be connected to respond to an output characteristic such as the output voltage of the electric valve means. When the system is arranged to control automatically the electric valve means, the phase of the manually adjustable periodic voltage is positioned so that it is substantially ineffective so far as the control of electric valve means is concerned. For example, in rectifier operation this voltage is displaced substantially 180 electrical degrees relative to the anode cathode voltage. When it is desired to effect transfer of control from the automatic to the manual means, the phase of the manually adjustable periodic voltage is advanced to substantial coincidence with the automatically controlled periodic voltage and the periodic voltage due to the automatic means is then removed. In this manner the transition from the automatic means to the manual means is effected without causing a material disturbance in the output characteristic of the electric valve means.

For a better understanding of our invention reference may be had to the following description taken in connection with the accompanying drawings and its scope will be pointed out in the appended claims.

Fig. 1 of the accompanying drawings diagrammatically illustrates an embodiment of our invention as applied to an electric valve rectifying system; and Fig. 2 represents certain operating characteristics thereof.

In Fig. 1 of the accompanying drawings there is diagrammatically illustrated an embodiment of our invention as applied to an electric valve system for transmitting power between an alternating current supply circuit 1 and a direct current load circuit 2 through electric translating apparatus comprising a transformer 3 and an electric valve means 4. A suitable circuit controlling means such as a switch 5 may be employed to connect and disconnect the translating apparatus from the supply circuit 1. The electric valve means 4 is preferably of the type employing an ionizable medium such as a gas or a vapor and may comprise a pair of anodes 6 and 7 and a single mercury pool cathode 8 within an enclosing envelope 9. Control members 10 and 11 are

associated with the anodes 6 and 7, respectively, and control the conductivities of the associated arc discharge paths which are provided by the anodes 6 and 7 and the cathode 8. As a means 5 for initiating ionization of the medium, which in the embodiment illustrated is mercury vapor, we may employ a suitable electrode 12 upon which there is impressed a suitable potential by apparatus not shown. The electric valve means 4 10 may also comprise holding anodes 13 and 14 which are energized by a circuit, not shown, to maintain the mercury vapor in an ionized state.

As a means for controlling the conductivity of the electric valve means 4, we provide an excitation circuit 15 which comprises an automatic means 16 and a manual means 17. The automatic means 16 impresses on control members 10 and 11 periodic voltages automatically variable in phase in accordance with a predetermined 20 controlling influence such as an output characteristic or the output voltage of the electric valve means 4. The automatic means 16 may be energized from any suitable source of alternating current correlated in phase and frequency 25 relative to the voltage of the alternating current circuit 1. In the embodiment shown in Fig. 1, the automatic means 16 is represented as being energized from the alternating current circuit 1 through a switch 18. The automatic means 16 30 comprises a transformer 19 having a primary winding 20 and secondary windings 21-24. The periodic voltages of the automatic means 16 are impressed on the control members 10 and 11 of electric valve means 4 through transformers 25 35 and 26. In order to control the phase of the periodical voltages produced by the automatic means 16 in accordance with the voltage of circuit 2, we provide electric discharge devices 27 and 28 which are preferably of the type employing an ionizable medium such as a gas or a vapor 40 and each comprises an anode 29, a cathode 30 and a control grid 31. The electric discharge devices 27 and 28 are associated with and receive power from secondary windings 21 and 23, respectively, of transformer 19. 45

The conductivities of the electric discharge devices 27 and 28 are controlled by control circuits 32 and 33, respectively. These circuits vary the time during the cycles of anode-cathode voltage of electric valve means 4 at which 50 the electric discharge devices 27 and 28 are rendered conductive, and hence control the output voltage of the electric valve means 4. The control circuits 32 and 33 each includes a phase shifting means which may be of the static-impedance type comprising a capacitance 34 and a resistance 35. Current limiting resistances 36 55 may be connected in series relation with the control grids 31 of electric discharge devices 27 and 28. The control circuits 32 and 33 are designed by proportioning of the capacitances 34 and resistances 35 so that the alternating components of voltages impressed on the control grids 31 are substantially retarded in phase relative to the anode-cathode voltages of the electric discharge devices 27 and 28. This angle of retardation may be substantially 90 electrical degrees. As a means for controlling the conductivities of the electric discharge devices 27 60 and 28 in response to an electrical condition of circuit 2 such as the voltage of circuit 2 we employ a suitable means such as an amplifier 37 or other voltage sensitive device which impresses on the control grids 31 a unidirectional voltage 65 which varies in magnitude in accordance with

the departure of the voltage of circuit 2 from a predetermined value. This unidirectional potential may vary throughout positive and negative ranges and may vary in magnitude in accordance with the voltage of circuit 2. Of course, the resultant voltage impressed on the control grids 31 is the sum of the alternating component and the unidirectional component so that the resultant voltage impressed on the grids 31 varies in phase in accordance with the voltage of circuit 2.

Where it is desired to impress on the control members 10 and 11 of the electric valve means 4 voltages of peaked wave form, we may employ parallel connected capacitances 38 and resistances 39 which are connected in series relation with the electric discharge devices 27 and 28. When the electric discharge devices 27 and 28 are rendered conductive, impulses of current are transmitted through the primary windings 20 of transformers 25 and 26 thereby inducing relatively large voltages of peaked wave form in the secondary windings. Although a particular type of circuit for producing voltages of peaked wave form is employed, it will be well understood by those skilled in the art that other types of circuits well known in the art for accomplishing this result may be employed without departing from our invention in its broader aspects.

The manually adjustable means 11 comprises a phase shifting circuit 40 which may be energized from a suitable source of alternating current such as circuit 1 through a transformer 41. The phase shifting circuit 40 may be of the static-impedance type comprising a capacitance 42 and a manually adjustable resistance 43. The output voltage of the phase shifting circuit 40 is impressed on the control members 10 and 11 of electric valve means 4 through a transformer 44 40 have a primary winding 45 and a secondary winding 46. It will be noted that the secondary winding 46 is connected in series relation with the secondary windings of transformers 25 and 26 so that the two periodic voltages effectively 45 act in series relation. Current limiting resistances 47 may be connected in series relation with the control members 10 and 11 of electric valve means 4.

To provide an indication of the phase relationship between the periodic voltage produced by the manual means 17 and the periodic voltage produced by the automatic means 16, we employ any suitable and conventional arrangement such as a synchroscope 48 which is connected 55 to the output circuit of the manual means 17 and to one of the output circuits of the automatic means 16.

The operation of the embodiment of our invention diagrammatically illustrated in Fig. 1 of 60 the drawings will be explained by considering the system when direct current is being supplied to the load circuit 2 from the alternating current supply circuit 1 through transformer 3 and electric valve means 4. The output voltage 65 of circuit 2, of course, may be controlled by controlling the conductivity of the electric valve means 4. It is understood by those skilled in the art that the voltage of circuit 2 is maximum when the arc discharge paths are rendered conductive near the beginning of the positive half cycles of anode-cathode voltage and that the output voltage of the electric valve means decreases as the electric valves are rendered conductive at later points in the positive half cycles. 70

When the system is arranged for automatic operation, the automatic means 16 is energized from the alternating current circuit 1 and the switch 18 is maintained in the closed circuit position. Electric discharge devices 27 and 28 are rendered conductive alternately to produce periodic voltages of peaked wave form which are impressed on the control members 10 and 11 by way of transformers 25 and 26. The phase of the impulses of the periodic voltage of peaked wave form produced by circuit 16 is controlled by the control circuits 32 and 33 and the amplifier 37. When the electric discharge devices 27 and 28 are rendered conductive, impulses of current of relatively large magnitude are transmitted through the primary windings of transformers 25 and 26 to generate periodic voltages of peaked wave form which are impressed on control members 10 and 11. The positive unidirectional biasing potential may vary in sign and magnitude in response to the voltage of the direct current circuit 2 to maintain the voltage of circuit 2 substantially constant.

The manual means 17, during the time when the automatic means is effectively controlling the conductivity of electric valve means 4, is adjusted so that the output voltage is substantially ineffective, that is, is adjusted so that the voltages derived from the phase shifting circuit 49 are substantially 180 electrical degrees out of phase with the anode-cathode voltages of electric valve means 4. When it is desired to effect transfer of the control of electric valve means from automatic to manual operation, the phase of the manually adjustable periodic voltage is advanced by adjustment of the resistance 43 to a position in which there is substantial phase coincidence between the output voltages of circuit 17 and the periodic voltages of the automatic means 16. This position of substantial phase coincidence may be detected by observance of the synchroscope 48. When such a condition of phase coincidence is established, the switch 18 may be opened thereby rendering ineffective the automatic means 16.

For a better understanding of the manner in which our invention operates, reference may be had to the operating characteristics shown in Fig. 2. Curve A represents the anode-cathode voltage for one of the arc discharge paths of electric valve means 4, for example, the arc discharge path between anode 6 and cathode 8. Curve B represents the critical voltage control characteristic for the electric valve means 4, that is, the voltage which must be impressed on the control member 10 to render the discharge path conductive. Curve C represents the phase of the output voltage of the manual means 17 when the system is under the control of the automatic means 16. Curve D represents the anode-cathode voltage of the electric discharge device 28 and curve E represents the critical control voltage for this electric discharge device. Curve F represents the resultant voltage impressed on grid 31 of electric discharge device 28 by control circuit 33 and the distance *a* represents the magnitude of the unidirectional biasing potential produced by the amplifier 37 which effects the shifting in phase of the resultant voltage impressed on the grid 31. Curve G represents the resultant voltage impressed on the grid 31 of the discharge device 28 when the unidirectional biasing potential is substantially zero.

For the particular conditions represented by curves D, E and F, the electric discharge device

28 will be rendered conductive at time *b* when the resultant voltage impressed on the grid 31, as represented by curve F, intersects the control characteristic curve E. Due to this action, there is generated in the secondary winding of transformer 25 a voltage of peaked wave form as represented by curve H. The voltage of peaked wave form is, of course, impressed on control member 10 of electric valve means 4 and is effective to render the electric valve means 4 conductive at time *b*. The electric discharge device 28 may be rendered conductive at a later time, for example, time *c* by impressing a negative unidirectional biasing potential on the grid 31, under which condition the voltage of peaked wave form will occur at about the same time. It is to be understood that the automatic control means 16 controls the phase of the voltage of peaked wave form as represented by curve H relative to the anode-cathode voltage as represented by curve A so that the output voltage of the electric valve means 4, or the voltage of circuit 2, remains substantially constant.

When it is desired to effect transfer of the control of electric valve means 4 from the automatic means 16 to the manual means 17, the phase of the output voltage of circuit 17 is advanced from the angle *d* to the angle *e* which is a position of substantial phase coincidence with the control voltage of the automatic means 16. In other words, the two periodic voltages provided by the manual means 17 and the automatic means 16 are acting substantially simultaneously and concurrently to render the electric valve means 4 conductive. This position of substantial phase coincidence of the periodic voltages of the manual means 17 and the automatic means 16 may be determined by observance of the synchroscope 48. When phase coincidence is established, switch 18 may be opened so that the automatic means 16 is deenergized. The system is then arranged for manual control. Due to the fact that the transition from automatic control to manual control is effected at a time when the two periodic voltages are in phase coincidence, the conductivity of the electric valve means 4 will not be changed abruptly and there will be substantially no disturbance caused thereby.

While we have shown and described our invention as applied to a particular system of connections and as embodying various devices diagrammatically shown, it will be obvious to those skilled in the art that changes and modifications may be made without departing from our invention, and we, therefore, aim in the appended claims to cover all such changes and modifications as fall within the true spirit and scope of our invention.

What we claim as new and desire to secure by Letters Patent of the United States is:

1. In a control system for an electric valve means having an anode, a cathode and a control member for controlling the conductivity thereof and having an associated excitation circuit comprising manual and automatic means for introducing into the excitation circuit separate periodic voltages which are impressed on the control member, the method of effecting transition from the automatic to the manual control means which comprises shifting the phase of the periodic voltage of the manual means to substantial coincidence with that of the automatic means and subsequently removing the periodic voltage produced by the automatic means.

2. In combination, an alternating current circuit, a load circuit, electric translating apparatus

- interconnecting said circuits and comprising an electric valve means having an anode, a cathode and a control member for controlling the conductivity thereof, an excitation circuit for energizing said control member, a control circuit for introducing into said excitation circuit a periodic voltage which varies in phase in accordance with an electrical condition of said load circuit, and manual means comprising a phase shifting circuit for introducing into said excitation circuit a second periodic voltage adjustable in phase to permit transition from automatic operation to manual operation.
3. In combination, an alternating current circuit, a load circuit, electric translating apparatus interconnected between said circuits and comprising an electric valve means having an anode, a cathode and a control member for controlling the conductivity thereof, an excitation circuit for energizing said control member comprising an electric discharge device for impressing on said control member a periodic control voltage, means for controlling the phase of said periodic voltage in accordance with an electrical condition of said load circuit, and manually adjustable means for introducing into said excitation circuit a second periodic voltage to permit transfer of the control of said electric valve means from automatic to manual operation.
4. In combination, an alternating current circuit, a load circuit, electric translating apparatus interconnecting said circuits and comprising an electric valve means having an anode, a cathode and a control member, an excitation circuit for energizing said control member and comprising an electric discharge device for generating a periodic voltage of peaked wave form, said electric discharge device being provided with a grid for controlling the conductivity thereof, means re-

sponsive to an electrical condition of said load circuit for impressing on said grid a unidirectional potential to control the phase of said periodic voltage of peaked wave form relative to the anode-cathode voltage of said electric valve means, and manually adjustable means for introducing into said excitation circuit a second periodic voltage adjustable in phase to permit transition of said electric valve means from automatic to manual operation.

5. In combination, an alternating current circuit, a direct current circuit, electric translating apparatus interconnecting said circuits and comprising an electric valve means having an anode, a cathode and a control member, an excitation circuit for said control member, means for introducing into said excitation circuit a periodic voltage of peaked wave form and comprising an electric discharge device and a capacitance which is charged by said electric discharge device, said electric discharge device being provided with a grid for controlling the conductivity thereof, a control circuit for energizing said grid and comprising a source of alternating voltage and means for impressing on said grid a unidirectional potential which varies in accordance with an electrical condition of said direct current circuit, and means energized from said alternating current circuit for introducing into said excitation circuit a voltage of substantially sinusoidal wave form adjustable in phase, means for advancing the phase of said alternating voltage of sinusoidal wave form to substantial phase coincidence with the periodic voltage of peaked wave form, and means for deenergizing said electric discharge device.
